(57) **CLAIM**

The ornamental design for a transportable automated pizza-making pod, as shown and described.

DESCRIPTION

FIG. 1 is a front view of a transportable automated pizza-making pod showing our new design;

FIG. 2 is a rear view of the transportable automated pizza-making pod shown in FIG. 1;

FIG. 3 is a side view of the transportable automated pizza-making pod shown in FIG. 1;

FIG. 4 is a top view of the transportable automated pizza-making pod shown in FIG. 1; and,

FIG. 5 is a top front perspective view of the transportable automated pizza-making pod shown in FIG. 1.

The broken lines shown in the figures form no part of the claimed design.

1 Claim, 5 Drawing Sheets
